(57) **CLAIM**

The ornamental design for a tip cable component of a measurement probe head assembly, as shown and described.

DESCRIPTION

FIG. 1 is a front-side isometric view of a tip cable component of a measurement probe head assembly.

FIG. 2 is a front view of the tip cable component of FIG. 1. FIG. 3 is a rear view of the tip cable component of FIG. 1. FIG. 4 is a rear-side isometric view of the tip cable component of FIG. 1.

FIG. 5 is a top view of the tip cable component of FIG. 1. FIG. 6 is a first-side view of the tip cable component of FIG. 1.

FIG. 7 is a bottom view of the tip cable component of FIG. 1; and,

FIG. 8 is a second-side view of the tip cable component of FIG. 1.

Environmental portions of the tip cable component of a measurement probe head assembly are shown in broken lines and form no part of the claimed design.
